BACK-PRESSURE CONTROL IN PRESSURE DRILLING

George S. Bays, Tulsa, Okla., assignor to Standard Oil and Gas Company, Tulsa, Okla., a corporation of Delaware

Application December 20, 1938, Serial No. 246,864

6 Claims. (Cl. 255—24)

This invention relates to a system of handling drilling fluids in connection with pressure drilling operations. More particularly it relates to a method and apparatus for controlling back pressure in such operations.

In drilling wells, particularly oil and gas wells, it has long been customary to use a drilling fluid, usually a so-called drilling mud, to carry away the cuttings, cool and lubricate the bit, build wall 10 and prevent the intrusion of unwanted fluids into the well. More recently drilling operations have been carried out in which the drilling fluid is under a pressure in excess of that corresponding to the hydrostatic pressure of the fluid column. 15 Such pressure drilling operations are particularly important in areas where heaving shale is encountered, especially in areas where the pressures encountered in a bore hole shift from that determined by the hydrostatic head to that controlled by the overburden or overlying earth 20 pressure. It is my belief that this shifting of pressure is sometimes quite abrupt, especially in Gulf Coast areas, in which case the pressure within less than 100 feet can change from one 25 based on approximately 470 pounds per 1000 feet in depth to one more than double that figure.

However this may be, pressure drilling operations are very useful to obtain a bottom hole mud pressure sufficiently high to mud off a caving or heaving formation without resorting to the use of excessive amounts of weighting materials; to keep oil, water or gas from coming 30 into the hole; to bring in a well without sealing off production with heavy drilling fluids; and to 35 drill or bring in a well with a controlled flow, thus preventing initial velocities in a producing formation which might break down the walls of the well and cause excessive caving or heaving.

The conventional method of circulating mud, 40 oil or other drilling fluid is down through the drill pipe and up through the annular space between the drill pipe and the casing although reverse circulation is commonly used in connection with pressure drilling operations. The drilling fluid discharged from the top of the well can be handled in a closed system without releasing its pressure by having an automatically controlled circulation pump floating on the line but this, of course, requires that the cuttings carried from the well be settled out under pressure. I have found that this is impractical at least when drilling through certain types of formations since the cuttings do not settle out satisfactorily in a pressure device. Moreover, high pressure settlers are expensive.

It has therefore been considered necessary in many pressure drilling operations to maintain the back pressure on the drilling fluid by the use of reducing valves or chokes through which the drilling fluid is vented to atmospheric pressure. 5 The mud then flows into the conventional settling pits or is otherwise handled at atmospheric or other relatively low pressure to remove cuttings and then picked up at this low pressure by the circulating mud pumps and reinjected into 10 the well. However, in using this system under Gulf Coast conditions I have found that even by using both vibrating screens and centrifuges for the elimination of cuttings, these cuttings cannot be eliminated satisfactorily. Apparently 15 the mud passing through a choke across which its pressure is reduced from, for instance, 1,000 pounds per square inch to atmospheric, is subjected to a very severe shearing action which 20 converts the shales or clays into a finely divided 25 or colloidal state. This raises the viscosity of the mud so high that it cannot be handled efficiently and at the same time greatly lowers its "weight" or density which is often artificially obtained by the use of expensive weighting materials. This loss of weight is due to the failure 30 to remove the shale cuttings from the mud and since these cuttings are of lower density than the average density of the mud there is a continual reduction in mud weight.

For these reasons I have found it essential either when the back pressure is controlled by an enclosed circulation system with pressure separation of cuttings or when the back pressure is controlled by the use of chokes, to control the 35 weight and viscosity of the drilling mud by continuously adding water to reduce viscosity and adding weighting materials to increase the specific gravity. Not only is this highly expensive but I have found it practically impossible. Thus 40 in a specific case, under Gulf Coast conditions, it was found that the weight of the mud could not be increased appreciably beyond 10 pounds per gallon and with the back pressure limited to 1,000 pounds per square inch it was calculated 45 that a 12½ pound mud was required to hold back the heaving shale. Not being able to obtain a mud weight above 10 pounds, the heaving shale finally closed in on the drill pipe, sticking it and 50 losing the hole.

The colloidal clay and shale troubles encountered in pressure drilling operations in certain Gulf Coast and other areas is not due to the high mud pressures used but rather to the shearing action which takes place when the pressure is 55

suddenly reduced across a choke. In other words, when the pressure is continuously and gradually reduced through the normal flow of the mud from about 1000 pounds per square inch to atmospheric 5 no trouble is encountered in removing the cuttings.

It is an object of my invention to provide new and improved methods of back pressure control 10 in pressure drilling operations. Another object of my invention is to provide apparatus for this purpose. A more detailed object of my invention is to provide methods for the more complete removal of cuttings from drilling fluids used in 15 pressure drilling operations. A further object of my invention is to provide drilling fluid handling systems in which the cuttings can be removed more completely and satisfactorily than has heretofore been the case and in which this is done without substantial loss of the energy available 20 by virtue of the pressure of the drilling fluid coming from a pressure drilling operation.

My invention will be described with particular reference to the accompanying drawing which is a simplified diagrammatic elevation, partly in section, of one form of apparatus in which my invention can be carried out.

In brief my invention contemplates the use of an hydraulic motor as a back pressure regulator. The high pressure drilling fluid is used to operate 30 such a motor and in the course of this operation its pressure is reduced without subjecting any appreciable part of the drilling fluid to any shearing action since it enters the cylinder or motor chamber at high pressure and leaves 35 at low pressure without any sudden pressure drop across an orifice as occurs when the pressure is reduced across a valve or choke.

Turning more particularly to the drawing, the well being drilled is not shown in its entirety but 40 only the parts which are important from the standpoint of the present invention. Casing 1 is equipped with master control gate valve 2 and packer or blow-out preventer 3 through which the drill pipe 4 carrying rock bit 5 is inserted. The 45 packer can, of course, be of any desired type, for instance the Hydril type, although a simple form is shown. Above this packer is the conventional equipment, including the rotary table 6, the kelly drive and associated devices, but these 50 have been omitted from the drawing. Above them the upper end of the kelly 7 (or the drill pipe itself if no kelly is used) is connected to swivel 8 through which drilling mud under high pressure is introduced from the discharge of mud pump 9 55 by means of line 10 and flexible hose 11.

Drilling mud thus introduced may be at a pressure which will depend upon many factors familiar to those skilled in the art. Generally speaking, the pressure at which the drilling fluid 60 is introduced will range from about 1500 to about 5000 pounds per square inch, typically about 3000 pounds per square inch. This drilling fluid passes down through the drill pipe to the base of the well and then up through the annular space between 65 the drill pipe and the casing. However, my invention is equally applicable to a system in which the circulation is maintained in the other direction, i. e. so-called reverse circulation. The drilling fluid at a back pressure of from about 70 500 to about 2000 pounds per square inch, for instance about 1000 pounds per square inch, passes from the annular space between tubing 4 and casing 1 out through line 12 which is preferably entirely free of chokes and other obstructions across 75 any substantial pressure drop would occur and

thence to a pressure reducer 13 which can be described as a pump with two fluid ends 14 and 15, end 14 running in reverse, i. e. as an hydraulic motor, the mud entering the cylinder at high pressure and doing work on the piston throughout the working stroke, at the end of which the cylinder is closed by a mechanical valve and pressure admitted to the opposite side of the piston, the mud which has already done its work being expelled to the atmosphere.

Thus pressure reduction chamber or motor end 14 of the pump takes in a cylinder full of high pressure drilling fluid through a suitable valve and discharges it at low pressure through another valve into line 16. If the fluid contains gas the 15 inlet valve can be closed well before the power stroke is completed to permit expansion but in any event no more than a minuscule portion of the fluid is subjected to any substantial pressure drop across the exhaust valve. In pump 12 the pressure is reduced, typically, from 1000 pounds per 20 square inch to atmospheric or other low pressure and the drilling mud at this low pressure passes to mud tank, pit or other mud settling chamber 17 in which the cuttings settle out. It 25 is, of course, possible to place a vibrating screen 18 or other cutting separator between pump 13 and mud pit 17 if desired.

Power made available by the expansion of the drilling mud in the power or motor end 14 of pump 13 can be utilized in various ways. Thus for instance, fluid end 15 can be used to pick up mud from the mud tank or pit 17 through line 19, act as a mixer and recirculate the mixed mud to the pit through valve 20 and line 21. However, this fluid end 15 operated by the high pressure drilling mud in motor end 14 can be made of small size relative to end 14 and can be utilized to boost the pressure on a small part of the drilling mud to the pressure at which it is introduced 40 through line 10 and hose 11. This can be accomplished by opening valves 22 and 23 and closing valves 20 and 24. Thus the energy made available by the expansion of the drilling mud is used to pump a quantity of drilling mud to the higher 45 pressure used for injection and fluid end 15 then operates in parallel with the main mud pump 9.

A still further method of using this energy is to close valves 20, 23 and 25 and open valves 22 and 24, thus using the fluid end 15 of pump 12 50 in series with the main mud pump 8, powered by steam or other external power, to handle the total amount of mud reinjected into the well.

The system of my invention need not be confined to the use of a reciprocating type motor 14 55 to reduce the drilling fluid pressure, as either single or multiple stage rotary gear or displacement pumps or other prime movers might be substituted as hydraulic motors, the main object being to release the pressure of the drilling fluid 60 without the use of a shearing choke, since pressure release is necessary to remove the drill cuttings efficiently.

While I have described my invention in connection with certain specific embodiments thereof, it is to be understood that these are by way of illustration and not by way of limitation and I do not mean to be bound thereby but only to the scope of the appended claims which should be construed as broadly as the prior art will permit. 70

I claim:

1. In a pressure drilling operation in which drilling fluid comes from a well at a high pressure carrying cuttings, the steps which comprise reducing the pressure on said drilling fluid to ap- 75

proximately atmospheric pressure without subjecting it to any substantial shearing action, removing cuttings from the drilling fluid at approximately atmospheric pressure, and reinjecting said drilling fluid, after removal of said cuttings, into said well at a high pressure.

5. 2. In a pressure drilling operation in which drilling fluid comes from a well at a high pressure carrying cuttings, the steps which comprise reducing the pressure on said drilling fluid by 10 causing it to operate an hydraulic motor, removing cuttings from the drilling fluid at approximately atmospheric pressure, and reinjecting said drilling fluid, after removal of said cuttings, into said well at a high pressure.

10. 3. In a pressure drilling operation in which drilling fluid comes from a well at a high pressure carrying cuttings, the steps which comprise reducing the pressure on said drilling fluid by 15 causing it to do mechanical work, removing cuttings from the drilling fluid at approximately atmospheric pressure, reinjecting said drilling fluid, after removal of said cuttings, into said well at a high pressure, and using said mechanical work to operate an auxiliary mud pump.

20. 4. In pressure drilling apparatus comprising a line for drilling fluid under pressure leading from a well, a drilling fluid settling chamber and means for reinjecting said drilling fluid from said settling chamber into said well, the improvement 25 which comprises a prime mover arranged to be operated by the drilling fluid under pressure flowing through said line and adapted to discharge

said drilling fluid into said settling chamber at greatly reduced pressure without subjecting it to any substantial shearing action.

5. In pressure drilling apparatus comprising a line for drilling fluid under pressure leading from a well, a drilling fluid settling chamber and means for reinjecting said drilling fluid from said settling chamber into said well, the improvement 10 which comprises a prime mover arranged to be operated by the drilling fluid under pressure flowing through said line and adapted to discharge 15 said drilling fluid into said settling chamber at greatly reduced pressure without subjecting it to any substantial shearing action, and an auxiliary drilling fluid pump operated by said prime mover and arranged to recirculate drilling fluid from and to said settling chamber.

6. In a pressure drilling apparatus comprising a line for drilling fluid under pressure leading from a well, a drilling fluid settling chamber and 20 means for reinjecting said drilling fluid from said settling chamber into said well, the improvement 25 which comprises a prime mover arranged to be operated by the drilling fluid under pressure flowing through said line and adapted to discharge 30 said drilling fluid into said settling chamber at greatly reduced pressure without subjecting it to any substantial shearing action, and an auxiliary drilling fluid pump operated by said prime mover and arranged to assist said means for reinjecting said drilling fluid from said settling chamber into said well.

GEORGE S. BAYS.
